STARTING DEVICE FOR HIGH COM-
PRESSION ENGINES

Russel D. Acton, Chicago, Ill., assignor to International Harvester Company, a corporation of New Jersey

Application July 31, 1935, Serial No. 33,952

4 Claims. (Cl. 123—48)

This invention relates to internal combustion engines. More specifically it relates to a starting system for compression ignition engines.

In the operation of compression ignition engines using a liquid fuel of low volatility the compression must be high particularly to secure ignition when starting a cold engine. With an engine of a size suitable for tractors and for uses requiring an equivalent power plant the effort required to rotate the engine crankshaft on compression is such that manual cranking is either impossible or impracticable. With air injection engines, such as widely used for marine engines, the engine may be started by driving it with compressed air until a speed is attained sufficient to carry through and start the engine on compression ignition.

Constructions have been devised utilizing a starting system in which a compression ignition engine is provided with means for initially lowering the compression ratio and operating with a volatile fuel mixture supplied by a carburetor and with spark ignition. The engine may then be manually cranked and operated on the Otto cycle until the shift is made to the Diesel cycle with compression ignition. The Wentworth Patent 1,225,295, discloses a starting system of this type in which the change over to Diesel operation is made by manually shifting the various controls. The Johnston Patent No. 2,032,755, dated March 3, 1936, which is assigned to the same assignee as this application, shows in an engine of the type in which the present invention is embodied a starting system incorporating a shifting mechanism operable by rotation of the engine to shift from Otto to Diesel cycle after a predetermined number of revolutions of the engine, the number being manually preselected by the operator. The system has proved satisfactory, but is unsatisfactory in the respect that the time of shift remains to be determined by the operator and may not correspond in any way to the theoretically correct time.

The object of the present invention is to provide a starting system for compression ignition engines incorporating means actuated by means responsive to a condition of engine operation to shift from low compression with spark ignition to high compression with compression ignition when the engine has attained a condition indicative of its ability to ignite and operate on compression ignition. More specifically the invention relates to the provision of a shifting means automatically operable to shift from Otto to Diesel cycle when the speed and/or the tempera-

ture of the engine indicate that the engine will ignite by compression and operate on the Diesel cycle.

Another object is to locate a temperature responsive device at a point in the engine adjacent the combustion chamber, which is indicative of the ability of the engine to ignite injected fuel by the heat developed by compression.

Another object is to incorporate a shifting means for changing from Otto to Diesel cycle by means of a governor for a fuel injection pump.

Other objects and the means by which they are attained will be apparent from the detailed description which follows and the drawings, in which:

Figure 1 is a side elevation showing the upper portion of an engine incorporating the starting system of this invention;

Figure 2 is a cross section taken substantially on the line 2—2 of Figure 4 of the injection pump showing the operating means for the speed responsive shifting means;

Figure 3 is an elevation showing a modified form of shifting means actuated by the heat sensitive device alone;

Figure 4 is an elevation of the fuel injection pump broken away on a vertical section, as shown by the section line 4—4 in Figure 2, to show the governor control incorporated in the pump;

Figure 5 is a sectional view transverse to the block of an engine which is provided with an auxiliary combustion chamber and means for operating on Otto or Diesel cycle.

Figure 6 is a detail of the linkage between the carburetor and the shifting mechanism; and,

Figure 7 is an elevation partially broken away in section to show the valve for switching from a carbureted mixture to air.

A portion of an engine is shown in Figure 1 including the upper portion of a block 10, cylinder head 11, and a valve cover 12, the engine shown being of the overhead valve type. A shaft 13 is shown arranged transversely and projecting laterally of the cylinder head 11, this being the shifting shaft, as will be hereinafter described.

A member 14 rigidly mounted on the shaft 13 includes a handle 15 for setting the shifting shaft against the action of a tension spring 16 secured to the handle and to a bracket 17 mounted on the cylinder head. The member 14 also carries a cam portion 18 terminating in a latch 19 adapted to engage a notch formed in a lever 20 pivotally mounted on the bracket 17. The connections of the shifting control devices with the

55

lever 20 will be described later in connection with the detailed description of these devices.

In so far as the shifting shaft 13 and its latch means are concerned this disclosure is substantially the same as that disclosed in the Johnston patent, previously referred to, in which the different elements utilized for operating the engine are shown more fully.

In the cross section of the cylinder head shown in Figure 5, the shifting shaft 13 can be seen in the background behind the other elements and portions of the head shown in section. A worm gear 21 on the shaft 13 engages a worm wheel 22 on a shaft 23 extending in the direction longitudinally of the engine, it being understood that this engine illustrated has a plurality of cylinders, the construction of each of which is exactly the same as the one shown in cross section.

The shaft 23 carries cams 24, each of which engages a rocker member 25 for each cylinder. One end of the rocker member is seated on a washer supported by a spring 26 mounted in a pocket formed in the cylinder head. The other end of the rocker member engages the upper surface of a member 27 screw-threaded on to the stem of a valve 28. Said valve controls communication between the main combustion chamber 29 of the engine and an auxiliary combustion chamber 30 utilized for lowering the compression of the engine for starting. The spring 31 maintains the valve 28 in seated position except when opened by action of the rocker member 25 when it is depressed by the cam 24. A spark plug 32 is mounted in the auxiliary combustion chamber 30 for ignition when the engine is operated on the Otto cycle. The overhead valve arrangement is shown, but will not be described in detail, as it is conventional and forms no part of the present invention.

A partial cross section and partial elevation of the air inlet and carbureting means is shown at the lower right hand Figure 5. A side elevation is shown partially in section in Figure 7. A control shaft 33 is connected by a lever 34 at its end and a link 35 with a lever 36 mounted on the shifting shaft 13, as best shown in Figure 6. A simple carburetor 33' is diagrammatically illustrated, to which fuel is supplied by a conduit 37. The shaft 33 carries a valve 34' operable to supply air only to the air inlet conduit 38 or to supply a volatile mixture from the carburetor 33'. This construction is shown more completely in the patent above referred to. In so far as this disclosure necessitates the showing of the elements making up an engine, it is believed that the parts shown satisfactorily illustrate the essential elements to define the novel starting system.

In Figure 5 a precombustion chamber 39 is illustrated. Fuel is supplied to this precombustion chamber as is conventional in the Diesel engine art through a conduit 39' and a nozzle 40' mounted in a supporting block 41' fitted in the upper end of the precombustion chamber. These members are shown only diagrammatically, as any conventional construction may be used. The precombustion products are discharged through the opening 40 into the main combustion chamber 29. There are certain specific locations in an engine cylinder adjacent the combustion chamber which are more indicative of the engine's ability to ignite on compression ignition than other locations. In the illustrated embodiment a heat responsive device 41 in the form of an expandable bellows containing a sensitive ex-

pansible fluid is located in a pocket 42 formed in the cylinder head. To rapidly transfer heat adjacent the opening 40 to the heat responsive unit, copper pins 43 are inserted in the head extending closely adjacent the interior of the combustion space. It is to be understood that the thermosensitive element may be located in any position where heat from the desired location in the combustion space may be readily transmitted.

A shaft 44 rigidly connected to the heat responsive device 41 extends through the insulated cover 45 and is pivotally connected to an operating lever 46. Said lever is pivoted intermediate its ends on a bracket 47 integral with the cylinder head. At its upper end the lever 46 is provided with a latch or hook 48, which is positioned to engage the upper edge of the latch lever 20 when it is engaged with the shifting shaft with the shaft in its low compression position.

At this point the operation of the expandable bellows can be best described. When the temperature in the combustion space around the opening 40 reaches a point at which the heat responsive device 41 is designed to operate, the lever 46 is unlatched from the lever 20 allowing the said lever to be unlatched from the shifting shaft.

In the modification shown in Figure 3 corresponding parts bear the same reference numerals as in Figure 1. The lever 20 is provided with an extension 49 which is connected by a spring 50 with the bracket 17. In the modification of Figure 3 the spring 50 acts to raise the latch lever 20 when the hook 48 is released, whereupon the spring 16 operates the shifting shaft to cut off the auxiliary compression chamber and to operate the other controls for shifting from Otto to Diesel operation.

As illustrated, the engine is provided with a fuel pump housed in a casing 51 secured at one side of the engine block 10. Said casing includes pump mechanism and a governing device therefor, as will be described. Said governing device also operates the shifting mechanism contained in the pump casing. A pump shaft 52 adapted to be driven from the engine crank shaft in timed relation with respect thereto by means of a flanged coupling 53 extends longitudinally of the pump casing 51. Said shaft carries a plurality of cams 54, each cam being positioned to operate a fuel injection piston 55 through a suitable force transmitting linkage. Said linkage consists of a lever arm 56 rotatably mounted on a shaft 56'. A roller 57 carried by the lever arm 56 contacts with the cam on the shaft 52, motion being transmitted through the lever arm to a tappet 58 which operates the pump piston 55. As is conventional in pumps of this nature, a variable stroke is provided for by varying the time of opening of a by-pass valve 59, as shown in Figure 2. This is accomplished by a lever arm 60, which is rotatably mounted on an eccentric 61 carried by a governor shaft 62. The other end of the lever arm 60 is carried by the piston operating tappet 58. By angular rotation of the governor shaft 62, the time of by-pass, as determined by movement of the lever arm 60, may be varied.

At one end of the casing 51 the shaft 52 carries a member 63 which pivotally supports on parallel axes two diametrically located governor weights 64. Said weights are provided with radially and inwardly extending portions 65, through which pins 66 extend. The pins 66 pivotally support blocks 67 which are positioned

in an annular channel formed between spaced radial extensions 68 of a sleeve 69. The sleeve 69 is slidably mounted on an extension of the shaft 52. Pressure exerted by the governor weights on the sleeve 69 is transmitted through a ball bearing assembly 70 to a cylindrical member 71, which is formed with a radially extending flange at one end for abutting the ball bearing assembly. A compression spring 72 mounted in the member 71 abuts a flanged collar 73 in contact with the inwardly extending flange on the member 71. Said spring at its other end abuts a stop 74, only a portion of which is illustrated. The spring acts to counterbalance the governor weight action.

The cylindrical member 71 is provided with spaced flanges 75, between which pins or other suitable means carried by a bell-crank member 76 are engaged. Movement of the cylindrical member transmits angular movement to the bell-crank member 76 which is pivoted on a pin 77 carried by the casing and mounted at right angles to the axis of the shaft 52.

The bell crank member 76 is formed with an extension arm 78 provided with gear teeth positioned to engage the bevel gear 79 mounted on the governor shaft 62. It will be understood by this construction that movement of the governor weights oscillates the shaft 62, thereby changing the angular position of the eccentric 61 to regulate the stroke of the injection pistons.

By means of a worm wheel 80 on the pump shaft 52 and a gear 81 on a vertical shaft 82 mounted in the casing 10, continuous angular movement is transmitted to said shaft. By means of a worm 83 on the shaft, as shown in Figure 2, continuous rotation is also transmitted through a worm wheel 84 to a shaft 85 mounted in the casing at right angles to the shaft 83 and in a substantially horizontal position. The shaft 85 carries a cam 86 which engages the face of a tappet member 87 slidably mounted in a portion of the casing 10. A pressure spring 88 abutting a flange on the tappet member 87 returns the tappet from raised position and maintains it in contact with the cam 86.

A member 89 in the form of a rod vertically positioned alongside the engine block provides means for actuating the trip of the shifting mechanism. Said rod passes through the latch lever 20 and is slidably with respect thereto, a nut 90 being threaded on the upper end of the rod above the latch member. Said nut provides for adjustment and has a means for providing for lifting the rod 89 when the cam 86 engages the latch lever and lifts it vertically.

The shift rod 89 is slidably mounted with respect to the casing and extends thereinto in alignment with the tappet 87. Means are provided for preventing angular movement of the rod 89 during reciprocation thereof illustrated as a key 91. The rod 89 terminates a substantial distance above the tappet 87, being provided with a pivoted extension lever 92, which is adapted under predetermined speed conditions of the engine to engage the tappet 87 for operating the shifting mechanism.

A transverse shaft 93, slidably mounted in a portion of the casing, is provided with a contact head 94 adapted to engage a cam 95 rigidly carried by the governor shaft 62. Said cam is mounted in an angular position with respect to the governor shaft so as to engage the transverse shaft 93 and move it in the direction of the lever 92 when the speed of the engine has at-

tained a predetermined rate at which the engine is capable of operating on high compression with compression ignition.

A hollow tappet member 96 is slidably mounted on an end portion of the shaft 93 of reduced diameter. A compression spring 97 abuts the extended head of the member 96 and an abutting washer 98 mounted on the reduced end portion of the shaft 93. The head portion of the member 96 engages a rounded extension 99 on the lever 92. A spring 100 is wrapped around the pivot pin connecting the lever 92 with the rod 89 and the ends of the spring are hooked over said elements to normally hold the member 92 in the position shown. In this position the tappet 87 does not engage the lever 92 to lift the rod 89.

The details of the pump and the injection system have not been shown or described. Injection lines 101 are shown connecting the injection pump with the top of the cylinder block at which points the injection lines connect with injection nozzles fitted in the precombustion chamber 39.

The operation of the mechanism for controlling shifting by heat alone has been described in connection with the description of the modification shown in Figure 3. As shown in Figure 3, the temperature actuated control acts in conjunction with the speed actuated controlling means. When the engine has reached a speed for which the mechanism is designed and adjusted to trip the shift from Otto cycle to Diesel cycle, the cam 95 has been rotated to move the shaft 93 a sufficient distance to engage the lever 92 with the head of the tappet 87. As this tappet is continuously reciprocating at a slow rate, it is possible that the engine speed at which lateral movement of the shaft 93 takes place may move the lever 92 when the tappet member 87 is in lifted position. It is to provide for this condition that the resilient construction is provided by the member 96 and the compression spring 97. This spring is compressed if the tappet member 87 is in raised position. However, as soon as it drops, being returned by the spring 88, the lever 92 is moved over into a position substantially parallel with the rod 89. Upon the next stroke of the tappet member 87 the rod 89 is lifted vertically, thereby exerting pressure on the latch lever 20. If the temperature of the engine is such at the point in contact with the heat responsive device 41 that the latch 48 has been moved out of restraining position, as shown in dotted lines in Figure 5, the lever 20 is immediately tripped. As soon as the shaft 14 is released it is rotated by the spring 16 to shift the controlling mechanisms, as previously described, for operation on the Otto cycle to operation on the Diesel cycle, the most important feature of this shift being the change in pressure. The mechanism for effecting this change is shown completely and described in detail. The other mechanisms are clearly shown in the Johnston patent previously referred to.

Under certain conditions of operation the temperature may not have reached the predetermined condition for which the latch 48 is constructed to disengage. To take care of this condition a stop member 102 is mounted on the rod 89 below the latch member 20. A compression spring 103 abuts the stop member 102 and the lower side of the latch lever 20. Until the latch 48 is disengaged the member 89 is merely 75

reciprocated against the compression spring 103. As soon as the latch 48 is disengaged the shifting shaft is tripped. Under some conditions the heat control may not be utilized, the shifting 5 being then dependent entirely upon the speed of rotation of the engine.

The mechanism herein described for shifting from Otto to Diesel cycle is merely representative of a means for providing shifting which is dependent upon the speed of the engine. It has been incorporated with the pump governor to reduce the mechanism required and to utilize an existing mechanism for an additional function. During actuation of the device the load on the governor would be sufficient to disturb proper sensitive governing action. However, as soon as the latch member 20 has been tripped, the cam 18 lifts said member and the rod 89 carried thereby to such a height that it no longer engages the 20 tappet 81. The pressure of the spring 100 is sufficiently small as to not apply pressure to the cam 95 sufficient to put a prohibitive load on the governor.

In the operation of a Diesel engine utilizing low compression for starting, it is very desirable that means be employed to prevent excess running on low compression. For example, the valve controlling communication between the auxiliary compression chamber 30 and the main combustion chamber 29 is easily burned by the rapid flow of burning gases through the communicating area. There are other reasons for shifting as soon as operation on the Diesel cycle is satisfactory. However, an attempt to shift before the engine conditions are proper for turning the engine over on high compression and for igniting the injected fuel results in failure to continue operation, and also results in excess oil dilution due to failure of the injected fuel in igniting and burning. This invention as above described contemplates a method and a mechanism for carrying out the method in which the shift from Otto to Diesel operation is accomplished at a theoretically correct time either by the temperature condition in the engine, by the speed of rotation of the engine, or by a combination of these two conditions. By this method and mechanism the operator is not dependent upon, as in previous constructions, shifting at the proper time.

It is to be understood that applicant has shown and described only certain forms of devices for shifting from Otto to Diesel operation upon the attainment of certain predetermined conditions resulting from engine operation and that he claims as his invention all modifications falling within the scope of the appended claims.

What is claimed is:

1. In an internal combustion engine formed with a combustion chamber, the combination of means for operating the engine on a volatile mixture with spark ignition and on low compression, means for operating the engine on high

compression with a non-volatile fuel and compression ignition, means operable by rotation of the engine for shifting from one operating means to the other, heat responsive means mounted in heat exchange relation with a portion of the engine combustion chamber at a location indicative of the engine's ability to ignite and operate on compression ignition, and means operated by said heat responsive means for effecting the actuation of the shifting means. 5

2. In an internal combustion engine, the combination of means for operating the engine on a volatile mixture with spark ignition and on low compression, means for operating the engine on high compression with a non-volatile fuel and compression ignition, means for shifting from one operating means to the other, actuating means operatively associated with the shifting means rendered effective by a condition of engine operation indicative of the engine's ability to rotate on high compression, and means operatively associated with the shifting means rendered effective by another condition of engine operation indicative of the ability of the engine to ignite with compression ignition effective to control the time of shifting to high compression. 10

3. In an internal combustion engine formed with a combustion chamber, the combination of means for operating the engine on a volatile mixture with spark ignition and on low compression, means for operating the engine on high compression with a non-volatile fuel and compression ignition, means for shifting from one operating means to the other, speed responsive means operated by the engine, means connecting said means to the shifting means operable to shift from low compression to high compression when the engine has attained a predetermined speed sufficient to ignite and operate on compression ignition, and heat responsive means in heat exchange relation with the engine operable to retard the shifting to high compression by the speed responsive operated means until the engine temperature is sufficient for operation on compression ignition. 30

4. In an internal combustion engine formed with a combustion chamber, the combination of means for operating the engine on a volatile mixture with spark ignition and on low compression, means for operating the engine on high compression with a non-volatile fuel and compression ignition, means operable by rotation of the engine for shifting from one operating means to the other, heat responsive means mounted in heat exchange relation with a portion of the engine heated during initial operation and at a location indicative of the engine's ability to ignite and operate on compression ignition, and means operated by said heat responsive means for effecting the actuation of the shifting means. 40
